UNITED STATES PATENT OFFICE.

CHARLES H. STONE AND CHARLES W. LIVINGSTON, OF SOUTH GROTON,
MASSACHUSETTS.

IMPROVED BURGLAR-ALARM.

Specification forming part of Letters Patent No. 38,136, dated April 7, 1863.

To all whom it may concern:

Be it known that we, CHARLES H. STONE and CHARLES W. LIVINGSTON, of South Groton, in the county of Middlesex and State of Massachusetts, have invented a new and Improved Burglar-Alarm; and we do hereby declare that the following is a full and exact description thereof, reference being had to the accompanying drawings, and to the letters of reference marked thereon.

Figure 1 is a side elevation of the machine complete. Fig. 2 is a longitudinal section through the center, showing the internal arrangement of the ratchet-gears and striking apparatus. Fig. 3 is a longitudinal section through the center, showing the spring and the lever that starts the alarm. Fig. 4 is a transverse section cut through the stop *h*, and shows the start *J* attached to the door and the lever *i*. It also shows the position of the ratchet wheel *c* and the crank-shaft *b* in the rear.

The same letters indicate like parts in all the figures.

The nature of our invention consists in constructing the alarm in such a manner that a door may be shut but cannot be opened without starting the alarm; also, of making such a combination of ratchet-gears, springs, &c., that a practical and effectual alarm may be constructed at a small expense.

To enable others skilled in the art to make and use our invention, we will proceed to describe its construction and operation.

We construct our alarm with a spring and two ratchet gears and pawls, with lever-crank and bell. The gears, pawls, spring, and lever are confined in a metal box. The spring *a* in Fig. 3 is firmly attached to the crank-shaft *b*, the ratchet-wheel *c*, and its pawl *k*. (Shown in Fig. 2.) The ratchet-wheel *d* and the double pawl *e* are so arranged as to operate the ham-

mer *f*, as shown in Figs. 2 and 4. The crank *g* and the stop *h* are so arranged as to hold the spring *a* stationary. (Shown in Figs. 1 and 3.) The lever *i* projects below the metal box to reach the start *J*, which operates the stop *h*. (Shown in Figs. 1 and 4.)

Operation: The alarm may be fixed to any convenient place on the door-frame, and the start *J* fixed to the door in such a position as to operate the lever *i*. The spring *a* is wound up by the crank *g*, and the stop *h* holds the power of the spring. The ratchet-wheel *c* is held by the pawl *k* that propels the ratchet *d*, and the ratchet-wheel *d* rocks the double pawl *e*, which operates the hammer *f* against the side of the bell. It will be seen that if the spring *a* is wound up, and the crank *g* resting on the stop *h*, that by shutting the door the start *J* simply crowds the lever *i* back, which forces the stop *h* a little farther forward, but on opening the door the start *J* moves the lever *i* forward and operates to throw back the stop *h*, and the whole force of the spring *a* comes on the ratchet *c* and the pawl *k*, which causes the ratchet-wheel *d* to move and the double pawl *e* to rock, which throws the hammer *f* with force and great rapidity against the side of the bell.

What we claim as our invention, and desire to secure by Letters Patent, is—

The combination of the spring *a* and wheel *c*, the pawl *k*, the wheel *d*, and the double pawl *e* with the hammer *f*; also, the combination of the lever *i* with the stop *h*, and crank *g* with the start *J*, constructed and operating substantially as described, and for the purposes set forth.

CHARLES H. STONE.

CHARLES W. LIVINGSTON.
